ENGINE STARTER

Frank H. Prescott, Anderson, Ind., assignor, by
mesne assignments, to General Motors Corpora-
tion, Detroit, Mich., a corporation of Delaware

Application June 8, 1931, Serial No. 542,806

37 Claims. (CL 290—38)

This invention relates to automatic starting devices for internal combustion engines, and more specifically, to devices of this kind which will automatically start the engine whenever the 5 ignition switch is closed and which will automatically operate to restart the engine if said engine should stop at any time as long as the ignition switch remains closed.

Devices of this general type are shown in the 10 prior art, as for instance, in the patent to Hasselbring No. 1,739,069, granted December 10, 1929.

In the device disclosed in the drawing, the engine starter is of the type in which the starting motor is connected to the motor through the 15 medium of a pinion which is rotated by the starting motor and which is axially slidable into and out of engagement with the flywheel gear by means other than the starting motor before the motor switch is closed to effect rotation of the 20 pinion. It will be understood, however, that the invention is not limited to this particular type of engine starting device.

In automatic engine starting devices of the 25 type shown in the patent to Hasselbring, an electromagnet has been used to effect the shifting of the driving pinion of the engine starting device and to close the switch of the starting motor, the circuit of such electromagnet being closed when the ignition switch is closed and the circuit through such magnet being automatically 30 broken by the action of the generator when the engine is operating under its own power. In such a device it is necessary to employ an electromagnet of considerable size in order to perform its 35 various operations and so large an electromagnet involves considerable expense.

It is the object of the present invention to provide 40 an automatic engine starting device of the character above referred to, which is simple in construction, positive in operation and relatively inexpensive to make.

A further object of the invention is to provide 45 a device of this character which includes means for delaying the re-starting of the engine subsequent to any stalling thereof at least long enough to permit the shaft of the starting motor to come to rest.

According to the present invention, these objects are attained by the use of a small electric 50 motor, the circuit of which is closed when the ignition switch is closed, and which is effective to move the starting motor pinion axially into engagement with the flywheel gear and to close the main switch of the starting motor so that the flywheel gear is driven thereby to start the en-

gine. The circuit of the small motor is broken when the engine is operating under its own power after which its shaft is reversely rotated by a spring to restore the various parts operated by the motor to normal position.

Further objects and advantages of the present invention will be apparent from the following description, reference being had to the accompanying drawing, wherein a preferred embodiment of one form of the present invention is 10 clearly shown.

In the drawing:

The single figure is a diagrammatic illustration of an automatic starting device constructed in accordance with the present invention. 15

In the drawing, a starting motor is diagrammatically illustrated at 10. This motor is provided with an armature shaft 12, which is splined, as indicated at 14 and an internally splined sleeve 16 engages splines 14 so that said sleeve 20 rotates with the shaft 12, but is slidable thereon as hereinafter described.

A pinion 18 is connected to one member of an over-running clutch indicated in its entirety by the reference numeral 20, the other member of 25 which is connected to the sleeve 16, integrally or in any other suitable manner, so that the pinion will rotate with the sleeve 16 after the main motor switch is closed and as long as the engine flywheel gear 9 is being turned by the pinion, but 30 as soon as the engine starts operating under its own power, the pinion may rotate independently of the sleeve 16 through the medium of such clutch. The specific construction of this clutch is not material so far as the present invention 35 is concerned and since the clutches of this character are known and in common use, the specific construction thereof will not be further described.

Slidable on the sleeve 16 and rotatable with 40 respect thereto, is a collar 22, which, when moved to the right by means hereinafter described, will operate through a coil spring 24, coiled around the sleeve 16 between the collar and the clutch 20 to move the driving pinion 18 toward the 45 flywheel gear. If the pinion 18 strikes a gear tooth of the flywheel gear 9 as it is thus moved, the spring will yield so that the collar moving means may continue its movement to close the main motor switch whereupon the shaft 12 is 50 effective to rotate the pinion to meshing position through the medium of the clutch, and the spring 24, which is under compression, will cause the pinion to jump into engagement with the flywheel gear teeth as is well known in the art.

The collar 22 is moved to engage the pinion with the engine gear by a lever 26 pivoted at 28, on some suitable support and provided with a yoke 30 at its lower end, the arms of which have 5 projecting lugs 32, which are received in a groove 34, formed on the collar 22, as shown in the drawing. At its upper end, the lever 26 is provided with an open end slot 36 which engages a pin 38 projecting from a nut 40 engaging the threaded end 42 of the armature shaft of a small motor indicated diagrammatically at 44, the shaft 42 being provided with a pin 46 extending therethrough to prevent the nut 40 from being disengaged from the shaft.

15 One end of the shaft 42 is connected to one end of a spring 48, in any suitable way while the other end of the spring engages a pin 54, or some other stationary part, so that as the shaft 42 is turned during the operation of the motor 44, to rock the lever 26 about its pivot in a counterclockwise direction, the spring 48 will be put under tension and, when the motor ceases to operate after the starting of the engine, the spring, which is an ordinary clock spring, will unwind 20 and restore the parts to the position shown in the drawing.

25 Mounted in any suitable manner in proximity to the lever 26, is a switch closing plunger 60, having a head 62 adapted to be engaged by a projecting shoulder 64 of said lever 26 and normally held in its open or inoperative position by a spring 66, received between the head 62 and a member 68, which supports the switch plunger. At the opposite end of the plunger 60, a bridge 30 contact 70 is provided which will engage the stationary contacts 12 and 14 when the switch plunger is in its operative or closed position to enable current to pass from battery 76 to ground at 78, and through the lead 80, contact 12, contact piece 70, contact 14, the connection 82, through armature and brushes of the motor 10 and the connection 84 back to the ground. Therefore, whenever the lever 26 is operated to move the switch plunger 60 to its operative or 40 closed position, the circuit is closed through the main starting motor which turns the shaft 12 and through the medium of the pinion 18, which is moved into engagement with the engine flywheel gear 9 before the switch plunger is moved 45 to its closed position, rotates the engine flywheel and starts the engine. After the engine is operating under its own power, the lever 26 is moved to its original position and the switch plunger is moved to its open position breaking 50 the circuit through the starting motor.

55 The small motor 44 is operated whenever the ignition switch is closed to move the lever 26 in a counterclockwise direction to effect movement of the switch plunger 60 in the manner above described. The ignition switch is indicated in its 60 entirety by the reference numeral 90, and has three contacts 92, 94, and 96, from which extend electrical connections 98, 100 and 102, which lead respectively, to the ignition mechanism, to 65 an automatically operated electromagnetic switch 104 in circuit with the motor 44 and to the generator circuit between the generator 134 and the battery 76. A three arm contact member 106, when moved to its closing position, 70 engages all of the contacts 92, 94 and 96. The connection 100 leads to a stationary contact 108 of the automatic switch 104, which is normally engaged by a movable switch arm 110, held in closed position by a spring 112. The other end 75 of arm 110 is connected by wire 114 through the

brush 116, 118 and armature of motor 44, to the ground. Therefore, when the member 106 is in closed position, current may flow from the battery to the ground through the connection 78, through the connections 107 and 102 to the switch contact point 96, the member 106, contact 94, connection 100, stationary and movable contacts 108 and 110, connection 114, brushes 116 and 118 and the armature of motor 44 back to the ground. The circuit of the motor 44 is, therefore, closed whenever the member 116 is in its closed position, resulting in the rotation of the armature shaft 42 and the operation of the lever 26 in a counterclockwise direction as previously described, to effect, first, the movement of the starting pinion 18 to the right into engagement with the flywheel gear 9 and thereafter the closing of the main starting motor switch which will result in the cranking and starting of the engine.

20 When the engine has started and is operating under its own power, the generator is operated in the usual manner to charge the battery 76 and becomes effective to break the circuit of the motor 44 by operating the electromagnetic switch 104 to separate the contacts 108 and 110. To this 25 end the switch 104 includes a solenoid 120, having a core 122 and a winding 124 connected to the ground as indicated at 126 and by wire 128 connected to the generator which is grounded as indicated at 130. A cut-out relay of ordinary 30 construction is indicated at 132 between the generator and the battery.

35 After the engine starts to run under its own power and the generator is operated to sufficient speed to generate current of approximately 2½ volts potential, the switch arm 110 is moved to break the circuit of the motor 44, and such circuit will remain broken as long as the generator operates at sufficient speed to generate current having a voltage of approximately 40 .2 volt. The difference in voltage required to separate the contacts 108 and 110 and that required to hold the contacts in open position is due to the fact that the air gap within the solenoid is reduced after the switch is opened, 45 so that much less voltage is effective to keep the switch open than is required to open it when closed. Thus it will be clear that the electromagnetic switch is held in its open position until the engine has practically ceased to run so that 50 motor 44 can not be rendered effective to close the circuit of the main starting motor, or effect engagement of the pinion 18 with the flywheel gear 9 until the flywheel gear has substantially stopped moving. This is important, because if 55 it were possible to cause engagement of the pinion 18 with the flywheel gear during the operation of the latter, it would result in stripping the teeth of the gear or pinion.

60 It is desirable that there always be some delay in meshing of the starting pinion with the flywheel gear and closing of the circuit of the main starting motor. This is necessary because the engine might be started and then stopped substantially immediately after it had started to run, 65 in which event the starting motor shaft would still be turning and the pinion 18 rotating relatively rapidly after the engine has stopped, because of the inertia of the parts. If it were possible to operate the lever 26 immediately, under 70 these conditions, movement of the pinion 18 to engage the gear 9 would be effected while the shaft of the starting motor was still rotating, resulting in probable breaking of the teeth of 75 gear or pinion. The device illustrated herein is

effective to prevent this immediate reoperation of the lever 26 because of the worm connection between the nut 40 and the shaft 42 of the small motor. Due to this worm connection, it takes 5 an appreciable time interval for the lever 26 to be rocked on its pivot sufficiently to effect engagement of the pinion and gear.

The small motor 44 is positive in its action and is relatively low in cost, being of substantially 10 the same size as motors employed in motor operated horns.

While the form of embodiment of the present invention as herein disclosed, constitutes a preferred form, it is to be understood that other 15 forms might be adopted, all coming within the scope of the claims which follow.

What is claimed is as follows:

1. Engine starting apparatus for automotive vehicles comprising in combination, a current 20 source, an ignition switch, a starting motor, a switch for effecting the connection of the current source and the motor, an auxiliary rotary motor for operating the main motor switch, and means for rendering said auxiliary motor effective 25 on closing of the ignition switch.

2. Engine starting apparatus for automotive vehicles comprising in combination, a current 30 source, an ignition switch, a starting motor, a switch for effecting the connection of the current source and the motor, an auxiliary rotary motor for operating the main motor switch, means for rendering said auxiliary motor effective on closing of the ignition switch, and means for rendering said auxiliary motor ineffective 35 when the engine is operating under its own power.

3. Engine starting apparatus for automotive vehicles comprising in combination, a current 40 source, an ignition switch, a starting motor, a switch for effecting the connection of the current source and the motor, an auxiliary rotary motor for operating the main motor switch, means for rendering said auxiliary motor effective on closing of the ignition switch, a generator adapted 45 to be operated by the engine and means operated by the generator for rendering said auxiliary motor ineffective.

4. Engine starting apparatus for automotive vehicles comprising in combination, a current 50 source, an ignition switch, a starting motor, a switch for effecting the connection of the current source and the motor, a motor driven pinion for operating the engine flywheel to start the engine, an auxiliary rotary motor for moving 55 said pinion into engagement with said flywheel, and means controlled by the ignition switch for rendering said auxiliary motor effective on closing of the ignition switch.

5. Engine starting apparatus for automotive vehicles comprising in combination, a current 60 source, an ignition switch, a starting motor, a switch for effecting the connection of the current source and the motor, a motor driven pinion for operating the engine flywheel to start the engine, an auxiliary rotary motor for moving 65 said pinion into engagement with said flywheel independently of the starting motor, means for rendering said auxiliary motor effective on closing of the ignition switch and a delayed operating connection between the auxiliary motor and the pinion whereby the engagement of the pinion with the engine flywheel is materially delayed.

6. Engine starting apparatus for automotive 70 vehicles comprising in combination, a current

source, an ignition switch, a starting motor, a switch for effecting the connection of the current source and the motor, a motor driven pinion for operating the engine flywheel to start the engine, an auxiliary motor for moving said pinion into engagement with said flywheel, means for rendering said auxiliary motor effective on closing of the ignition switch, and an operating connection between the auxiliary motor and pinion; including a worm drive, whereby the engagement of the pinion with the flywheel gear is materially delayed. 5

7. Engine starting apparatus comprising, in combination, an engine starting motor, a pinion operated thereby and movable into mesh with a gear of the engine to be started, a smaller rotary electric motor, means operated thereby for closing the circuit of the starting motor to cause the engine starting motor to operate to crank the engine, and means for controlling the smaller 10 motor. 15

8. Engine starting apparatus comprising, in combination, an engine starting motor, a pinion operated thereby and movable into mesh with a gear of the engine to be started, a smaller rotary electric motor, a current source, means operated 20 by the smaller motor for connecting the current source with the engine starting motor to cause the latter to crank the engine, and means for controlling the smaller motor. 25

9. Engine starting apparatus comprising, in combination, an engine starting motor, a pinion operated thereby and movable into mesh with a gear of the engine to be started, a smaller rotary electric motor, a current source, means operated 30 by the smaller motor for connecting the current source with the engine starting motor and for shifting the pinion into mesh with the engine gear, and means for controlling the smaller motor. 35

10. Engine starting apparatus comprising, in combination, an engine starting motor, a pinion operated thereby and movable into mesh with a gear of the engine to be started, a rotary electric motor, means operated by said rotary motor for directly moving the pinion into mesh with the engine gear and for causing the engine cranking motor to be energized independently of said rotary motor, and means for controlling said rotary motor. 40

11. Engine starting apparatus comprising, in combination, an engine starting motor, a pinion operated thereby and movable into mesh with a gear of the engine to be started, a smaller electric motor, a shaft rotated by the smaller motor in one direction, means operated by said shaft when 55 driven by the smaller motor for shifting the pinion into mesh with the engine gear and for causing the engine cranking motor to operate, a spring operable when the smaller motor ceases to operate for rotating the shaft in the opposite direction 60 to cause the pinion to be demeshed from the engine gear and the engine starting motor to cease operation, and means for controlling the smaller motor. 65

12. Engine starting apparatus comprising, in combination, an engine starting motor, a pinion operated thereby and movable into mesh with a gear of the engine to be started, a smaller electric motor, a current source, a shaft rotated by the smaller motor in one direction, means operated 70 by said shaft when driven by the smaller motor for shifting the pinion into mesh with the engine gear, and for connecting the engine starting motor with the current source, a spring operable when the smaller motor ceases to operate for ro- 75

- tating the shaft in the opposite direction to cause the pinion to be demeshed from the engine gear, and for disconnecting the engine starting motor from the current source, and means for controlling the smaller motor.
13. Engine starting apparatus comprising, in combination, an engine starting motor, a pinion operated thereby and movable into mesh with a gear of the engine to be started, a smaller electric motor, a current source, a screw threaded shaft rotated by the smaller motor in one direction, a non-rotatable nut threaded by the shaft axially thereof, a pinion shifting lever operated by the nut, a switch operated by the lever for connecting the current source and engine cranking motor, a spring operable when the smaller motor ceases to operate for rotating the shaft in the opposite direction to cause the pinion to be demeshed from the engine gear, and for effecting the opening of the starting motor switch, and means for controlling the smaller motor.
14. Engine starting apparatus comprising, in combination, an engine starting motor, a pinion operated thereby and movable into mesh with a gear of the engine to be started, a smaller rotary electric motor, means operated thereby for causing the engine starting motor to operate to crank the engine, and means responsive to engine operation for rendering the smaller motor inoperative.
15. Engine starting apparatus comprising, in combination, an engine starting motor, a pinion operated thereby and movable into mesh with a gear of the engine to be started, a smaller rotary electric motor, means operated thereby for causing the engine starting motor to operate to crank the engine, a manually operable switch for causing the smaller motor to operate, and a switch automatically responsive to engine operation for rendering the smaller motor inoperative.
16. Engine starting apparatus for automotive vehicles comprising, in combination, a current source, an ignition switch, a starting motor, a starter switch for closing the circuit between the current source and the starting motor, means for closing said starter switch upon closing of the ignition switch when the engine is not running and to hold said switch closed until the engine begins to run if said ignition switch remains closed and effective to close the starter switch whenever the engine stops if the ignition switch is in closed position, said switch closing means including transmission mechanism so constructed as to delay the closing of the starter switch for an appreciable interval after the closing of the ignition switch or after any stopping of the engine when the ignition switch is closed, and means for preventing operation of the starter switch when the engine is running.
17. Engine starting apparatus for automotive vehicles comprising, in combination, a current source, an ignition switch, a starting motor, a starter switch for closing the circuit between the current source and the starting motor, a motor driven pinion for operating the engine flywheel to start the engine, means for moving said pinion into driving engagement with said flywheel upon closing of the ignition switch when the engine is not running and effective to so move the pinion whenever the engine stops while the ignition switch is in closed position, said means for moving the pinion including transmission mechanism so constructed as to delay the engagement of the pinion with the flywheel for an appreciable interval after the closing of the ignition switch
- or after any stopping of the engine when the ignition switch is closed, and means for preventing movement of the pinion into engagement with the flywheel when the engine is running.
18. Engine starting apparatus for automotive vehicles comprising, in combination, a current source, an ignition switch, a starting motor, a starter switch for closing the circuit between the current source and the starting motor, a motor driven pinion for operating the engine flywheel to start the engine, means for moving said pinion into driving engagement with said flywheel and for closing the starter switch upon closing of the ignition switch when the engine is not running and effective to so move the pinion and close the switch whenever the engine stops while the ignition switch is in closed position, said means for moving the pinion and closing the starter switch including transmission mechanism so constructed as inherently to delay the engagement of the pinion with the flywheel and the closing of said switch for an appreciable interval after the closing of the ignition switch or after any stopping of the engine when the ignition switch is closed, and means for preventing movement of the pinion into engagement with the flywheel and the closing of the starter switch when the engine is running.
19. Engine starting apparatus for automotive vehicles comprising, in combination, a current source, an ignition switch, a starting motor, a starter switch for closing the circuit between the current source and the starting motor, a motor driven pinion for operating the engine flywheel to start the engine, a lever for moving said pinion into driving engagement with said engine flywheel, means operable upon closing of the ignition switch when the engine is not running for operating said lever and effective to operate the lever whenever the engine stops while the ignition switch is in closed position, said operating means including transmission mechanism so constructed that the movement of the pinion to engaging position with the flywheel is delayed for an appreciable interval after the closing of the ignition switch or after any stopping of the engine if the ignition switch is closed, and means for preventing operation of the lever when the engine is running.
20. Engine starting apparatus for automotive vehicles comprising, in combination, a current source, an ignition switch, a starting motor, a starter switch for closing the circuit between the current source and the starting motor, a motor driven pinion for operating the engine flywheel to start the engine, a lever for moving said pinion into driving engagement with said engine flywheel and for closing the starter switch, means operable upon closing of the ignition switch when the engine is not running for operating said lever and effective to operate the lever whenever the engine stops while the ignition switch is in closed position, said operating means including transmission mechanism so constructed that the movement of the pinion to engaging position with the flywheel and the closing of the starter switch is delayed for an appreciable interval after the closing of the ignition switch or after any stopping of the engine if the ignition switch is closed, and means for preventing operation of the lever when the engine is running.
21. Engine starting apparatus for automotive vehicles comprising, in combination, a current source, an ignition switch, a starting motor, a starter switch for completing the circuit between

the current source and the starting motor, a member for operating said starter switch, means effective on closing of the ignition switch when the engine is not running for operating said member, and means for effecting a relatively slow movement of said member with respect to its operating means so constructed that inherently the closing of the starter switch is delayed for an appreciable interval subsequent to the closing of the ignition switch.

10 22. Engine starting apparatus comprising in combination, an engine starting motor, a pinion operated thereby and movable into engagement with a gear on the engine to be started, a rotary electric motor adapted to be connected with the same source of current as the starting motor, means operated by the rotary motor for directly moving the pinion into engagement with the engine gear and for connecting the starting motor with the current source, and means for controlling the operation of said rotary motor.

15 23. Control apparatus for internal combustion engines, comprising in combination, a current source, a starting motor adapted to receive current from said source and normally disconnected from the engine and having an armature shaft extending therefrom, a shiftable member slideable on said shaft for establishing driving connection between the starting motor and the engine, an auxiliary motor having a rotary armature shaft, means whereby rotation of the armature shaft of the auxiliary motor moves the slideable member on the shaft of the starting motor to establish driving connection between said starting motor and the engine, and means for controlling the operation of the auxiliary motor.

20 24. Control apparatus for internal combustion engines, comprising in combination, a starting motor, a current source for supplying current to said starting motor, a circuit between said starting motor and current source, an auxiliary rotary motor also in circuit with said current source and adapted when operative to cause the starting motor to become effective to drive the engine and means for controlling the operation of said auxiliary motor.

25 25. Control apparatus for internal combustion engines, comprising in combination, a starting motor, a current source for supplying current to said starting motor, a circuit between said starting motor and current source having a starter switch therein, an auxiliary rotary motor also in circuit with said current source and adapted when operative to close said starter switch to cause the starting motor to become effective to drive the engine, and means for controlling the operation of said auxiliary motor.

30 26. Control apparatus for internal combustion engines, comprising in combination, a starting motor normally disconnected from the engine, a current source, a circuit between the starting motor and current source, a starter switch in said circuit, an auxiliary rotary motor also in circuit with said current source and adapted when operative to close said starter switch and establish driving connection between the starting motor and the engine, and means for controlling the operation of said rotary motor.

35 27. Control apparatus for internal combustion engines, comprising in combination, a starting motor, a current source for supplying current to said starting motor, a circuit between said starting motor and current source having a main starter switch therein, an auxiliary rotary motor for operating said switch and also in circuit with

the current source, and manually and automatically operated switches for controlling the operation of said auxiliary motor.

40 28. Control apparatus for internal combustion engines, comprising in combination, a starting motor, a current source for supplying current to said starting motor, a circuit between said starting motor and current source, an auxiliary rotary motor also in circuit with said current source and adapted when operative to cause the starting motor to become effective to drive the engine, an ignition switch and means whereby operation of said ignition switch controls the operation of said auxiliary motor.

45 29. Control apparatus for internal combustion engines, comprising in combination, a starting motor, a current source for supplying current to said starting motor, a circuit between said starting motor and current source, an auxiliary rotary motor also in circuit with said current source and adapted when operative to cause the starting motor to become effective to drive the engine, an ignition switch and means whereby closing of the ignition switch causes the auxiliary motor to become operative.

50 30. Control apparatus for internal combustion engines, comprising in combination, a starting motor, a current source for supplying current to said starting motor, a circuit between said starting motor and current source, an auxiliary rotary motor also in circuit with said current source and adapted when operative to cause the starting motor to become effective to drive the engine, an ignition switch, means whereby closing of the ignition switch causes the auxiliary motor to become operative and an automatic switch operated by the engine to cause the auxiliary motor to become inoperative when the engine is running under its own power.

55 31. Control apparatus for internal combustion engines, comprising in combination, a starting motor, a current source for supplying current to said starting motor, a circuit between said starting motor and current source having a starter switch therein, an auxiliary rotary motor also in circuit with said current source and adapted when operative to close said starter switch to cause the starting motor to become effective to drive the engine, an ignition switch, and means whereby closing of the ignition switch causes said auxiliary motor to become operative.

60 32. Control apparatus for internal combustion engines, comprising in combination, a starting motor, a current source for supplying current to said starting motor, a circuit between said starting motor and current source having a starter switch therein, an auxiliary rotary motor also in circuit with said current source and adapted when operative to close said starter switch to cause the starting motor to become effective to drive the engine, a manually operable switch for causing the auxiliary motor to become operative and an automatic switch controlled by operation of the engine to cause said auxiliary motor to become inoperative when the engine runs under its own power.

65 33. Control apparatus for internal combustion engines, comprising in combination, a starting motor normally disconnected from the engine, a shiftable member operative to establish driving connection between the starting motor and the engine, a current source with which said starting motor is in circuit, an auxiliary rotary motor also in circuit with said current source and adapted when operative to move said shiftable member

into position to establish driving connection between the starting motor and the engine, and means for controlling the operation of said auxiliary motor.

34. Control apparatus for internal combustion engines, comprising in combination, a starting motor normally disconnected from the engine, a shiftable member operative to establish driving connection between the starting motor and the engine, a current source, a circuit between said current source and said starting motor, a starter switch in said circuit adapted to be closed by movement of said shiftable member, an auxiliary rotary motor also in circuit with said current source and adapted when operative to move said shiftable member into position to establish driving connection between the starting motor and the engine and to close said starter switch, and means for controlling the operation of said auxiliary motor.
35. Control apparatus for internal combustion engines, comprising in combination, a starting motor normally disconnected from the engine, a shiftable member operative to establish driving connection between the starting motor and the engine, a current source, a circuit between said current source and said starting motor, a starter switch in said circuit adapted to be closed by movement of said shiftable member, an auxiliary rotary motor also in circuit with said current source, and adapted when operative to move said shiftable member into position to establish driving connection between the starting motor and the engine and to close said starter switch, a manually operable switch for causing the auxiliary motor to become operative and an automatic switch operable by the engine to cause said auxil-

iary motor to become inoperative when the engine is operating under its own power.

36. Control apparatus for internal combustion engines, comprising in combination, a current source, a starting motor adapted to receive current from said source and normally disconnected from the engine, a drive shaft operable by said motor, a member adapted to be moved laterally to establish driving connection between the starting motor and the engine and in driving relation with said drive shaft in either normal or shifted position, an auxiliary rotary motor, means operated by rotation of said auxiliary motor to move said member laterally to connect the starting motor in driving relation with the engine, and means for controlling the operation of said auxiliary motor.

37. Control apparatus for internal combustion engines, comprising in combination, a current source, a starting motor adapted to receive current from said source and normally disconnected from the engine, a drive shaft operable by said motor, a member adapted to be moved laterally to establish driving connection between the starting motor and the engine and in driving relation with said drive shaft in either normal or shifted position, an auxiliary rotary motor, means operated by rotation of said auxiliary motor to move said member laterally to connect the starting motor in driving relation with the engine, a switch for connecting the starting motor with the current source, means operated by said laterally shiftable member as it is moved to establish driving connection between the starting motor and engine to close said switch, and means for controlling the operation of said auxiliary motor.

FRANK H. PRESCOTT.
